UNITED STATES PATENT OFFICE.

OLIVER D. WOODRUFF, OF SOUTHBURG, CONNECTICUT.

MEAT-CUTTER.

SPECIFICATION forming part of Letters Patent No. 352,023, dated November 2, 1886.

Application filed June 1, 1886. Serial No. 203,753. (No model.)

To all whom it may concern:

Be it known that I, OLIVER D. WOODRUFF, a citizen of the United States, residing at Southbury, in the county of Hartford and 5 State of Connecticut, have invented certain new and useful Improvements in Meat-Cutters, of which the following is a specification.

My invention relates to the class of meat-cutters used for mincing meat or cutting into 10 comparatively small fragments pieces or masses of similarly-yielding substances.

The object of my invention is to provide a machine of this class, that shall be few in the 15 number of its parts, simple in arrangement, and more effective in its operation when compared with prior machines of its class of like size.

In the accompanying drawings, Figure 1 is a side elevation of a machine embodying my 20 improvements. Fig. 2 is a view in central vertical section of the casing and in side view of the feed-screw. Fig. 3 is a view in cross-section of the device on a plane passing through the cutters and denoted by line $x-x$ of Fig. 1. Fig. 4 is a view in cross-section of the device 25 on a plane denoted by line $y-y$ of Fig. 1, showing the method of securing the knives in dovetailed sockets. Fig. 5 is a view in plan of the lower half of the main body of the casing, showing the arrangement of the ribs and the 30 longitudinal knife; and Fig. 6 is a side elevation of the conical head, showing the cam-groove and peripheral knives.

In the accompanying drawings, the letter a denotes the casing of the machine, which casing is made up of two parts, a' and a'' . The 35 part a' has an inlet through the hopper b , near one end of the casing. A series of ribs, c , extend from end to end upon the inner curved wall of part a' . These ribs are preferably 40 flattened and merge into the surface of the wall just in front of the edge of the cutter d . This cutter is seated in a socket in the inner wall of part a' and is held within it by the screw d' , by means of which the edge of the 45 cutter is held adjusted with reference to the periphery of the feed-screw e . It will be noticed that the parts of the ribs c which stand transversely to the case are slightly inclined toward the delivery end, while the connecting 50 parts extend longitudinally with the case, giving the appearance of steps. By this peculiar

form the meat, when brought in contact with the thread of the feed-screw, is more rapidly fed along and cut into pieces by the cutter d preparatory to entering the cam-groove in the 55 conical head at the end of the feed-screw. The steps in the rib may be either coarse or fine. In the end wall, a^3 , of part a' a bearing is formed that supports the shaft e' , upon which the feed-screw e is supported. 50

The casing as a whole resembles two truncated cones joined at their bases, the longer cone being the part a' , above described, and the shorter one consisting of the part a'' , the two parts being preferably secured together 65 by means of a screw-thread, although any other well-known means or method may be employed. The part a'' is preferably made conical to facilitate the adjusting of the knives. The outer end of the part a'' has an opening 70 that forms the bearing for the other end of the feed-screw shaft e' . The feed-screw conforms in general outline to the frusto-conical interior part, a' , of the casing, the outer end of which screw has a shoulder, e^2 , that prevents the 75 movement of the feed-screw toward the hopper. A spiral thread is formed on the feed-screw and the pitch of the thread varies, causing a like variation in the groove between the threads from the hopper to the outlet end of 80 the casing. Beyond the termination of the feed-screw e and connecting therewith is a conical head having a cam-groove to receive the substance from the feed-screw e . Upon the 85 outer surface of this conical head are secured the peripheral knives g , arranged lengthwise and inclined to their axes. The cutting-edges of these knives are preferably slightly raised, so as to touch the under surface of the 90 perforated conical shell of part a'' without having any other part coming in contact therewith. These knives bridge the cam-groove, which forms an opening turning substantially at right angles to the axis of the feed-screw, although the thread is carried out so as to connect its 95 groove with the cam-groove, as denoted at f^2 . Surrounding these peripheral knives g , which may be of any convenient number, is a conical shell perforated with the delivery-holes h' , the edges of which form cutters that are opposed 100 to the knives g in the cutting of the material by the rotating of the knives and feed-screw.

This conical shell is made, preferably, of thin tool-steel bent to shape and secured by means of rivets to the annular ends of the part a^2 or a single casting of steel or malleable iron.

5 In making the device, the inclined knives g are preferably secured by inclining the opposite edges and forcing them into dovetailed sockets in the feed-screw, although other ordinary means of securing the knives in place may of course be adopted. The knives having been secured in place, the cutting-edges g' of the knives are turned or ground so that they are equidistant from the axis of the feed-screw, the proper clearance being made back 15 of the cutting-edge.

I do not limit myself to any particular method of forming this conical shell, the feature of my improvement in this regard being the peculiar arrangement of it in part a^2 of the machine and opposed to the peripheral knives borne upon the rotary feed-screw.

The delivery-holes h' can be multiplied indefinitely and the capacity of the machine thereby increased by extending the conical head and shell, while at the same time the delivery-holes will not be any farther from the axis. Consequently the cutter will do this increased work without materially increasing the power to operate it.

30 I am aware that prior patents show meat-cutters operated by a feed-screw having radial knives in connection with a perforated disk which delivers the product horizontally, and the same are hereby disclaimed. In such a construction only a limited number of delivery-holes can be made without forming said holes so far from the axis of the feed-screw as to resist the movement thereof with greater leverage.

40 In order to bring the cutting-edges of the opposed knives g and h close together to cut properly, the part a^2 is screwed upon part a' until the edges are brought close together, when the stop device i , which consists of the pawl 45 pivoted to the body part of the casing, with its end adapted to engage the ratchet formed in the edge of the other part, a^2 , so that when the latter has been screwed onto the part a' the end of the pawl may be set against a tooth of 50 the ratchet to prevent unscrewing.

A feature of my improvement in regard to the feed-screw consists in forming the groove with a steep pitch upon the side toward the outlet of the machine, as shown at j , with a 55 more gradual slope upon the other side of the groove.

I claim as my invention—

1. In a meat-cutter, the combination, with a casing having interior ribs interrupted by a 60 lengthwise knife secured within the casing, of a rotary feed-screw supported within the casing, and bearing knives that co-operate with openings in the casing at the outlet thereof, all substantially as described.

55 2. The combination of a casing made in two parts lengthwise, one part having an inlet and interior ribs and the other having an out-

let, and a feed-screw supported within the casing having a conical head bearing lengthwise knives inclined to the axis of said head and 70 co-operating with a perforated conical shell on the other part of the casing, all substantially as described.

3. The combination of a casing made in two parts lengthwise, the one part having an 75 inlet and interior ribs, the other part being conical, and having holes whose edges form cutters when acted upon by knives within said part and adjustable on the other part, to bring the cutting-edges of the holes and internal knives together, and a rotary feed-screw supported within the casing, all substantially as described.

4. The combination of the part a' , having an inlet and interior ribs, a conical part, 85 a^2 , threaded to fit upon the part a' , a stop device secured to the casing and limiting the movement of one part upon the other, a grooved feed-screw having connected therewith a conical head that bears knives inclined to the axis 90 of said head, and a perforated shell in the body part a^2 , all substantially as described.

5. In a meat-cutter, the combination of the casing made in two parts lengthwise and having an inlet and outlet, the conical perforated shell in the outer part of the casing surrounding knives, and the feeding mechanism within the inlet part of the casing, all substantially as described.

6. The combination of a casing having 100 inner ribs and an inlet and outlet, a rotary feed-screw having a groove of varying pitch from the hopper to the outlet end of the feed-screw, a conical head having the cam-groove, the inclined knives that bridge said cam-groove, and a cone-shaped perforated shell, the edges of the holes of which form cutters that co-operate with the knives that bridge said cam-groove, all substantially as described.

7. The combination of a casing having 110 interior ribs and an inlet and outlet, a rotary feed-screw supported within the casing, and having a groove with a steeper surface on the side of the thread toward the outlet of the casing than on the side toward the inlet, and a 115 conical head having a cam-groove, the inclined knives that bridge said groove, and a cone-shaped perforated shell with openings having cutting-edges, all substantially as described.

8. The combination of a casing made in 120 two parts lengthwise, one part having an inlet and interior ribs and the other part being cone-shaped and bearing at the outlet peripheral knives, a rotary feed-screw within one 125 part of the casing, the conical head in the other part of said casing, and the inclined knives extending across the grooves of said head, all substantially as described.

9. The combination of a casing having an 130 inlet and outlet and composed of two parts lengthwise, a rotary feed-screw supported within the casing and having a conical head, said feed-screw having a shoulder that by contact with the other part of the case prevents

lengthwise play of the feed-screw, and inclined knives borne on the conical head at the end of the feed-screw, whose thread is carried out to connect its groove with the cam-groove of the head, all substantially as described.

10. The combination of the casing part a' , having an inlet, b , interior ribs c , a lengthwise knife, d , for cutting the material into pieces preparatory to entering the cam-groove, conical part a^2 , secured to the other part by a screw-thread, a stop device consisting of a pawl borne on one part of the casing and with its outer end opposed to the ratchet on the part a^2 , a perforated conical shell in the part a^2 , a rotary feed-screw supported in the casing and having a lengthwise groove, and a conical head having cam-groove and bearing inclined knives that bridge said groove and co-operate with the knife on the casing, all substantially as described.

11. The combination of a casing having an inlet and outlet end composed of two parts lengthwise, of a rotary feed-screw supported within the casing and fitting loosely in the conical part of the casing, and having a shoulder that by contact with the casing prevents lengthwise play of the feed-screw, the conical head at the end of said feed-screw, and inclined knives borne on the conical head, said knives having their cutting-edges slightly raised above the periphery of the conical head, all substantially as described.

12. In a meat-cutter, the combination of a feed-screw, a head rotated with said feed-screw and bearing peripheral knives, and a case having peripheral openings, substantially as described, and for the purpose specified.

13. In a meat-cutter, the combination of a feed-screw, a head rotated with said screw and bearing peripheral knives, a case having peripheral openings, and the longitudinal knife affixed to the case, substantially as described, and for the purpose specified.

14. In a meat-cutter, the combination of a case having interior ribs composed of short inclined and longitudinal portions in the form of steps, substantially as shown, a feed-screw, and cutting mechanism at or beyond the end of the feed-screw, said feed-screw and ribs being adapted to feed the material to said cutting mechanism, substantially as described, and for the purpose specified.

15. In a meat-cutter, the combination of a feed-screw, a head rotated with said feed-screw and having a cam-groove which opens into the groove of the feed-screw, and peripheral knives bridging said cam-groove, substantially as described, and for the purpose specified.
